TOOL WITH EXTENSION SPACED FROM HEAD

Samuel Eliot, Newton, Mass.

Application May 20, 1950, Serial No. 163,164

3 Claims. (Cl. 7—8.1)

1

This invention relates to a general utility and tool of the percussive or hammer type in which there is provided a handle and a striking head transversely fixed at the end of the handle, as is commonly embodied in hammers used by carpenters, masons, machinists, and various other artisans.

In using a hand tool of the hammer class, it often is the case that the worker finds a need for using the tool in hand to secure various other kinds of mechanical advantage, such as to apply a leverage, to "jimmy" a clinched member, and generally to pull, pry, cut, straighten, and turn various structural members, as well as to hold or rotate annular bodies in the manner of a wrench.

The present invention aims to provide a general utility type of hand tool which is designed to meet many of such needs of the worker, and to devise in one hand tool a combination of striking head and handle member with certain other instrumentalities which are so arranged as to cooperate with the handle and striking head in one way or another to provide for varied novel functioning. It is also an object of the invention to provide a simple, efficient, and conveniently applied hand tool which can be cheaply manufactured and which is extremely durable and wear-resistant.

These and other objects and novel features will be more fully understood and appreciated from the following description of a preferred embodiment of the invention selected for purposes of illustration and shown in the accompanying drawings, in which:

Fig. 1 is a side elevational view of the improved general utility hand tool of the invention;

Fig. 2 is a fragmentary front elevational view of the striking head of the tool and adjacent portions thereof;

Fig. 3 is a plan view; and

Fig. 4 is a vertical cross-section taken on the line 4—4 of Fig. 3, and further suggesting one typical application of the device utilized as a wrench.

Referring in detail to the structure shown in the drawings, numeral 10 denotes a handle of wood, aluminum or other suitable material, which has its upper end solidly fitted into the body portion 12 of the tool, as may be more clearly observed in Fig. 4. As shown therein the body portion 12 is preferably constructed with a handle opening of some tapered shape through which the handle extends to be locked in place by means of a permanent wedge 14. The latter member

2

is made an integral part of the tool and extends transversely between two opposite sides of the body portion 12 so that it serves to divide the handle extremity into two split ends, as suggested in Fig. 3. These split ends are conveniently cut off and made to conform to the contour of the upper side of the hammer member.

Extending upwardly from the body portion 12 along one side thereof is a raised striking head 16 formed with a flat striking face 18. The face 18 may be located in various positions of angularity with respect to the vertical axis of the handle 10, and preferably will be set in such relative position that the face lies in a plane nearly parallel to the vertical axis of the handle, thereby taking advantage of the extended leverage resulting from the projection of the striking head above the extremity of the handle. For some purposes this extended leverage effect is a desirable advantage and it will be seen that the striking head presents a rounded upper surface 20 which lies above and in back of the striking face 18 and which projects well above the end of the handle extremity 10 to make possible other advantages hereinafter described in connection with other parts of the tool.

As an instance of one desirable application of the raised striking head, attention is directed to the opening 22 transversely located through the head which may be employed, for example, in straightening lengths of bent pipe or other tubular bodies which have been twisted or deformed out of a straight line position. By slipping such a tubular body or pipe through the hole 22 of the striking head, a highly desirable lifting or twisting force may be exerted. By wedging the annular opening 22 into engaged relation with such a tubular body, an excellent torque or twisting force may be delivered where it is desired to deform or twist the work which is being held. If desired, means consisting of serrated edges, or other roughened surfaces, or other holding devices, may be incorporated in the hammer surfaces constituting the opening 22 for further facilitating engagement of this part of the hammer with various types of work as, for example, in holding and stretching barbed wire, rope, and the like.

At the under side of the head 16 there is also provided means for chopping or cutting. The cutting means may, for example, conveniently take the form of two spaced-apart cutting edges 24 and 26. These are conveniently formed by removing intermediate portions 28 of the tool so that they lie at a lower level than the cutting

edges, as suggested in Fig. 2. The edges themselves may be formed with outer bevelled sides 26a and 24a to facilitate sharpening, if so desired. In the embodiment shown in the drawings the cutting edges 24 and 26 are curved, as is more clearly shown in Fig. 4, and it will readily be seen that such curved cutting edges may be conveniently employed to carry out either right or left cutting as well as various shearing and chopping operations as, for example, in connection with dressing poultry, cutting wood, rope, pipe, cable, and various other bodies. Since the cutting edges are arranged at one side of the handle below the striking head, it is convenient to use the tool in the same relative position as is assumed in carrying out a hammering or striking operation. Thus at one and the same time, a workman may first strike a percussive blow and by merely advancing the lead of the tool slightly, effect a cutting or shearing blow, a function which, in many instances, saves a workman time and effort in order to perform a desired operation.

At the opposite side of the body portion 12, from that occupied by the striking head, there is provided an extension 30 which projects upwardly at an angle to the handle 10 in a position such that it may constitute a lever portion. The effect of the lever is accentuated by forming the extension with a lower convex surface 32 which functions in the nature of a pinch bar or similar tool to pry or pull apart clinched members, as well as achieving various other operations.

To further increase utility in this respect, the extension 30 is preferably bifurcated to form an inverted claw which may be used in the ordinary manner for removing nails, spikes, and other holding devices. It will be observed that with the claw in its inverted position, as described, there is afforded a leverage which is developed along an opposite line of leverage to that ordinarily available in a carpenter's hammer where the claw is curved in the opposite dimension. For some types of operation where it is impossible to apply the handle of the conventional carpenter's hammer, the inverted claw arrangement is extremely desirable and effective. Also, the outside curved face of the claw 32 can be used as a curved striking head or hammer for shaping tin or copper sheeting, as well as hammering out dents. In addition, it will be apparent that the claw points are in substantially parallel relation and provide two closely associated edges which can be used as a screw driver for both small and large screws, slotted plates, etc.

In accordance with the invention I further provide for a desirable wrench portion which is arrived at by having the upper sides of the striking head 16 and the extension 30 merge with one another to form a generally concaved bearing surface which is useful in engaging against various types of annular bodies, such as pipes, or round cross-section stock of various classes of materials, as well as square and hexagonal nuts of varying diameters.

Since it may also be desirable to exert a rotative force on such bodies, there has further been provided teeth 34 extending transversely across the curved upper side of the extension 30 in stepped relation, as shown in Fig. 4, and these teeth cooperate with the relatively more sharply curved upper side of the striking head 16 to engage a work piece 36 and permit a turning force to be applied through the handle 10. Since the

upper side of the striking head 16 presents a varying arc of curvature, it will be apparent that a considerable range of sizes of tubular or annular bodies may be dealt with quickly and conveniently in the manner of a set Stilson wrench. For example, the arrangement described may be applied as a bung puller, a pipe fitting tool for usage in connection with large nut or bolt heads, either round or square, and various other similar applications. The improved tool may also be employed very advantageously in breaking, chopping and shearing ice deposits as, for example, on board ship and at other places where icy conditions are encountered.

15 The tool described has utility in many different connections wherein the component parts may cooperate with one another in a desirable manner. Particularly this tool was devised to serve as a wrecking instrument and an ice breaking tool. 20 For example, in breaking through a plaster wall or in breaking into a thin sheet of ice, the need is for an impact head which can be driven through the yieldable body of plaster, ice, or similar substances. However, in the usual hammering devices for this purpose the impact head tends to go through too far, with the result that the neck of the handle of the tool has to act as a stop element, which is undesirable for various reasons. It is pointed out that by forming the 25 extension 32 of the tapered body portion such that this extension projects upwardly and angularly away from the impact head, there is produced by the merging of this extension, with the body portion, a useful elongated body section 30 which operates to limit the extent to which the tool head may be driven into a yieldable body.

Moreover, assuming, for example, that the tool head has been driven into a plaster and lathe wall 40 and that the extension 32 comes to bear on the exterior surface of the wall, perhaps bearing against a stud, or other structure member, the body portion handle and tool head can then be rotated around the extension which acts as a 45 fulcrum, and a very desirable leverage and tearing effect can be developed, particularly on a body such as one of plaster or a sheet of ice. The same general effect may be produced in breaking through certain types of cartons made 50 of heavy corrugated paper and reinforced paneling. In the case of paper cartons or paper panels, a further desirable effect has been found to be possible by the limited shearing action of the two edges which extend from the flat face of 55 the tool head downwardly and inwardly to the body portion in parallel spaced-apart and relieved relationship. Moreover, when the tool is rotated with the extension 32 functioning as a fulcrum 60 the head and cutting edges can cooperate to simultaneously cut and lift out a partially severed tab which is useful in breaking through certain types of packing cases.

With respect to the transverse bore in the tool head still further cooperative effects may be developed. Let it be supposed, for example, that there is a body of pipe having a free end with the remainder of the pipe body being attached to a wall, and let it further be assumed that it is desired to bend the pipe end away from the 65 wall while the remainder of the body portion is maintained in place; in such an instance the free end of the pipe may be passed through the bore in the tool head and the handle, body portion, and extension 32 are then rotated for a short arc 70 until the extension bears against the supporting 75 wall.

surface to which the pipe is secured. The extension then constitutes a fulcrum and the handle and body portion, together with the tool head and the pipe, are rotated about this fulcrum with the pipe being subjected to a leverage of considerable magnitude which can produce a desirable bending.

Various other situations suggest themselves where the several different features of the tool may cooperate with one another to produce useful operations.

While I have shown a preferred embodiment of the invention, it should be understood that changes and modifications may be resorted to in keeping with the spirit of the invention as defined in the appended claims.

Having thus described my invention, what I desire to claim as new is:

1. An improved hand tool including a tapering body portion having a handle aperture formed therethrough, a handle secured in the aperture, said body portion including an annularly shaped tool head which extends upwardly and angularly away from the body portion at one side thereof, said tool head presenting a flat striking surface, an extension element extending upwardly and angularly away from the body portion in an opposite direction from the tool head, said extension and body portion cooperating to form an elongated body section which limits the extent to which the tool head may be driven into a yieldable body, and said extension, when the tool head has been embedded in a yieldable body, comprising a fulcrum about which the body portion and handle may be rotated to remove the tool head from the yieldable body.

5 2. A structure as defined in claim 1, in which the tool head is further formed with two spaced-apart relieved cutting edges which extend from the flat striking face of the tool head inwardly and downwardly to merge with the said body portion, said cutting edges being adapted to cut two spaced-apart parallel kerfs.

10 3. A structure as defined in claim 1, in which the tool head is formed with a transverse bore extending substantially at right angles to the axis of the said handle, said bore being adapted to receive therein a tubular member and to exert a force on the tubular member when the body portion and tool head are rotated about the extension element with the latter in a rigidly supported position.
